UNITED STATES PATENT OFFICE.

ELMER L. HAHN, OF McALLEN, TEXAS.

CABINET CAMP TABLE.

Application filed August 20, 1927. Serial No. 214,324.

This invention relates to new and useful improvements in tables and cabinets, and aims to provide a combined cabinet and table for use by campers, tourists, and the like.

5 In carrying out the present invention there is provided a cabinet unit constructed to provide a series of compartments for bread, jellies, salt and pepper, and other edibles as well as compartments for dishes, silver, and 10 similar ware. Furthermore, the construction of the cabinet is such that the same may be readily opened, and that when in opened condition, certain walls of the cabinet will afford a relatively large table so that meals 15 may be eaten thereon.

The invention further aims to provide a combined device of this character wherein there is provided supporting legs for detachable association with the ends of the cabinet, 20 the same being of such a length as to permit the same to be stored within a tray provided within the cabinet so that the cabinet may be readily disposed within an automobile or secured to the running board 25 thereof.

The most important object of the present invention is to provide a combined device of the aforementioned character that is of relatively simple construction and inexpensive 30 of manufacture and one that is highly adaptable for use while on extended motoring trips.

With the foregoing and other objects in view as the nature of the invention will be 35 better understood, the same comprises the novel form, combination and arrangement of parts hereinafter more fully described, shown in the accompanying drawings and claimed.

40 In the accompanying drawings forming part of this application, wherein like reference characters indicate corresponding parts:

Figure 1 is an end elevation of my improved combined cabinet and table, the 45 hinged walls of the cabinet being disclosed by the dotted lines as in open position to provide a table.

Figure 2 is a side elevation of the cabinet 50 per se.

Figure 3 is an enlarged transverse section through the cabinet, half of the top and one

side thereof being open for providing a table at this side of the cabinet.

Figure 4 is an elevation of one side of the 55 cabinet when open.

Figure 5 is a similar view of the other side of the cabinet.

Figure 6 is a top plan view of the cabinet when fully opened, and 60

Figure 7 is a roof perspective of one pair of legs constructed for ready attachment to or removal from one end of the cabinet, two sets of these legs being provided whereby the cabinet may be supported in elevated 65 position.

Now having particular reference to the drawings there is disclosed a cabinet designated generally by the reference character A. This cabinet is preferably of elongated 70 formation as disclosed in Figures 1, 2, 4, 5 and 6 and of rectangular shape in cross section as disclosed in Figure 3. This cabinet construction includes among other elements a bottom wall 5, a pair of end walls 6-6 75 and a central perpendicular partition wall 7 that extends throughout the length of the cabinet intermediate the sides thereof for dividing the same into compartments at opposite sides of the cabinet. 80

As clearly disclosed in Figure 3 the upper edge of this partition 7 terminates beneath the upper edges of the end walls 6-6 so that a relatively narrow tray 8 may be disposed within the cabinet directly above the partition 7 and rested thereon, the ends of this tray 8 being further supported by transverse cross cleats 9-9 arranged upon the inner faces of the end walls 6-6 directly at the upper edge of said partition 7, see Figure 5. 85

Within the compartment of the cabinet A at one side of the partition 7 and through an area slightly greater than one-half the length of the cabinet there is provided vertically extending longitudinally spaced partitions 10 for providing a series of fruit jar or container compartments 11. The upper ends of these partitions 10 terminate beneath the upper edge of the longitudinally extending partition 7 so as to provide a space for a sliding drawer 12 beneath the tray 8 within which may be disposed silver ware or the like. 95 100

Within the end of the compartment at this particular side of the cabinet A opposite from that end carrying the partitions 10 is a pair of relatively widely spaced partitions 13—13 that extend to the edge of the longitudinal partition 7 and extending longitudinally of which are vertically spaced bars 14 that are secured at their ends to the front edges of the partitions 13—13, which partitions and bars 14 provide a compartment for dishes as suggested by the dotted lines in Figure 4.

Arranged within the compartment at the opposite side of the longitudinally extending partition 7 and adjacent one end wall 6 thereof is a vertical partition 15 between which and the adjacent end walls is shelf board 16, whereby there are provided compartments within which may be arranged small containers such as mustard jars, salt and pepper shakers, etc. Provided for disposition within the main compartment of the container A at the side of the partition 7 is a metallic bread box 17 of a length less than the length of its particular compartment so that other containers may be arranged between the bread box 17 and said partition 15 as suggested in Figure 5.

Hinged to the opposite longitudinal edges of the bottom wall 5 of the cabinet A are side walls 18—18 that are connected at their opposite ends to the ends of the tray supporting cleats 9—9 by chains or other flexible connections 19. Hinged to the other longitudinal edges of said side walls 18—18 are lid sections 20—20, which when the walls 18—18 are extended upwardly into closed position may be swung downwardly upon the tray 8 and interconnected by any suitable fastener for maintaining the sides and top of the cabinet closed and for obviously retaining the various articles within their compartments therein. Furthermore, it will be appreciated from a consideration of Figures 3 and 6 on the dotted lines in Figure 1 that when the walls 18—18 are swung downwardly to horizontal position there will be provided at opposite sides of the cabinet A table or writing boards.

Arranged upon the end walls 6—6 of the cabinet are suitable carrying handles 21—21, while arranged directly beneath these handles are headed pins 22—22. Beneath the pin at each end wall of the cabinet and adjacent the lower edge thereof is a pair of spaced headed pins 23—23, which pins are for the purpose of permitting supporting legs for the cabinet to be detachably associated with the cabinet.

Constructed for association with each end of the cabinet is a pair of similar constructed L-bar legs 24—24, the inner walls of which extend beyond the outer walls at the upper ends and which walls are notched as at 25—25 for engagement over the respective

headed pin 22 at the proper end wall of the cabinet. Furthermore, the inner walls of each pair of legs are formed at their edges with transversely extending notches 25—25 for engagement over the headed pins 23—23 at the end of the cabinet. Pivottally attached to the inner wall of one leg of each pair of legs is a brace bar 26 formed at its lower edge and at its free end with a notch 27 for engagement over a headed pin 28 carried by the complementary leg as more clearly disclosed in Figure 7. Obviously after the legs 24—24 have been properly associated with the pins at a particular end of the cabinet A said legs are interconnected by the bars 26 to prevent the movement of the same with respect to each other. Furthermore, it will be readily apparent that the legs at opposite ends of the cabinet may be readily associated therewith and as readily detached therefrom. When removed from the cabinet, these legs are to be arranged within the tray 8 at the top of the cabinet A as suggested by the dotted lines in Figures 3 and 6.

In view of the foregoing description when considered in conjunction with the accompanying drawings it will at once be apparent that I have provided a highly novel, simple and extremely useful cabinet camp table that is well adapted for all the purposes heretofore designated, even though I have herein shown and described the invention as consisting of certain detail structural elements it is nevertheless to be understood that some changes may be made therein without affecting the spirit and scope of the appended claims.

Having thus described the invention, what I claim as new and desire to secure by Letters Patent is:—

1. Knock-down supporting means for elevated bodies comprising a pair of horizontally spaced projections at each end of a body, a projection at each end of the body at a point above the pair of projections, a pair of supporting legs for each end of the body, the legs of each pair being formed at one of their ends with longitudinally extending notches, said legs being each formed at a point adjacent its notched end with a transversely disposed notch, the legs of each pair being adapted to overlap at their notched ends so that said notches will register to receive the upper projections on the body, while the adjacent notches of the leg members receive the horizontally spaced projections on the body, and a member for connecting the respective pairs of legs together at their intermediate portions.

2. Knock-down supporting means for elevated bodies comprising a pair of horizontally spaced projections at each end of a body, a projection at each end of the body at a point above the pair of projections, a

pair of supporting legs for each end of the body, the legs of each pair being formed at one of their ends with longitudinally extending notches, said legs being each formed at 5 a point adjacent its notched end with a transversely disposed notch, the legs of each pair being adapted to overlap at their notched ends so that said notches will regis-

ter to receive the upper projections on the body, while the adjacent notches of the leg 10 members receive the horizontally spaced projections on the body, and a breakable connection between the legs of each pair at their intermediate portions.

In testimony whereof I affix my signature.
ELMER L. HAHN.
